(57) **CLAIM**

The ornamental design for alligator rope, as shown and described.

DESCRIPTION

FIG. 1 is a perspective view of alligator rope showing my new design;

FIG. 2 is a left side elevational view thereof, it being understood that the FIG. 2 through 7 views are shown at a reduced scale from that of FIG. 1;

FIG. 3 is a right side elevational view thereof;

FIG. 4 is a bottom view thereof;

FIG. 5 is a front elevational view thereof;

FIG. 6 is a rear elevational view thereof; and,

FIG. 7 is a top plan view thereof.

The claimed alligator rope is used by teachers to keep the children grouped when going for a walk.
